BURTON NEAL, OF ST. LOUIS, AND GEORGE H. HEBEBRAND, OF KINLOCH, MISSOURI.

PERCENTAGE FEEDER.

Application filed March 26, 1926. Serial No. 97,494.

This invention relates to power-driven feeding machines of the type generally known as "percentage feeders," which are designed to uniformly deliver regulated quantities of 5 the product being fed.

In prior devices of this character, the capacity of the feeders is usually varied by varying the speed of rotation of the feed wheel or other feeding member, which is usually actuated intermittently. Such devices are more or less lacking in uniformity of operation and they are, moreover, not susceptible of very accurate or close adjustment for varying the quantity of the product fed.

15 Machines of this character find a very wide application in flour mills, for use in blending grains, flour, and the like, and it is very desirable that a machine of this character should be capable of nice adjustment and 20 should operate with a high degree of uniformity.

It is the general object of our invention, therefore, to provide a percentage feeder, in which novel means are provided for varying 25 the quantitative feed of the device, such means permitting of accurate and close adjustment, and the machine, as a whole, operating uniformly under any given adjustment.

A further object of the invention relates to 30 the provision of means for adjusting the feed of the device, which is associated with a scale, whereby the operator can set the machine accurately to provide a given quantitative feed of material, and by observing the 35 scale, will know at all times the amount of material being fed through the machine. Our invention is characterized by the fact that the variation in the feed is effected by varying the capacity of the feeding member in place 40 of merely varying its rate of movement.

The invention is illustrated in the accompanying drawings, in which—

Figure 1 is a view in front elevation of a feeding machine constructed according to our 45 invention;

Figure 2 is a sectional view on the line 2—2 of Figure 1;

Figure 3 is a sectional view on the line 3—3 of Figure 2;

50 Figure 4 is a view similar to Figure 2, but showing a different position of the segmental members of the feed drum; and

55 Figure 5 is a broken sectional view showing the manner of pivoting the segmental members in the end walls of the feed drum.

Referring now to the drawings, the nu-

meral 1 indicates a casing having an inlet opening 2 at its top through which material flows to the feeder, and an outlet opening 3 at its bottom through which the material is 60 discharged. The casing 1 is provided with side walls 4 and 4^a. The numeral 5 indicates a feed drum which comprises circular heads 6, 7, and a sectional shell consisting of segmental members or leaves 8, each of which is 65 provided at its outer end and at either side with projections 9 (Figure 5), which project into suitable apertures formed in the heads 6 and 7 near the peripheries thereof, and by means of which the leaves 8 are pivotally 70 mounted at their outer sides in said heads. Projecting centrally from the head 6 and fixedly secured at its inner end to said head is a sleeve bearing 10, which is rotatably mounted in the wall 4. Secured on the outer end of this 75 sleeve is a pulley 11 which is rotated by a belt 12 driven from any suitable source of power (not shown). Projecting centrally from the head 7 is a sleeve bearing 13 which is also fixedly secured to the head and is rotatably mounted in the side wall 4^a. Rotatably mounted in the sleeve bearings 10 and 13 is a shaft 14, which is adapted to be turned manually through a greater or less arc to move the leaves 8 of the feed drum. To effect such 80

movement, we secure centrally of the shaft 14 a disk 15, and pivotally secure to said disk near the periphery thereof, the inner ends of a series of arms 16, corresponding in number to the number of the leaves 8, which, in the 90 present instance, is six. The outer ends of these arms are pivotally connected at 17, respectively, to the outer or free ends of the leaves 8. By an inspection of Figure 2, it will be seen that when the leaves 8 are in their 95 outermost position, so as to form a cylindrical shell, the arms 16 are positioned, respectively, to one side of diametrical lines of the shell, so that when the disk 15 is turned in an anti-clockwise direction, the outer or free 100 ends of the leaves 8 will be drawn downward by the arms 16 of a greater or less extent to a position corresponding to that shown in Figure 4. This movement of the leaves is for varying the quantitative feed of the drum, as 105 hereinafter explained. The shaft 14 is adapted to be manually turned to move the disk 15 in the manner just described, and for turning the shaft 14 and disk 15, and for indicating the extent to which the feed of the drum 110 is correspondingly varied, we provide the following mechanism:

Fixedly secured on the end of the sleeve bearing 13 opposite to that having the pulley 11 is a disk 18, provided on its periphery with two pins 19 located, respectively, at diametrically opposite points of the periphery. The numeral 20 indicates a hollow circular head, the inner end of which encircles and rests upon the periphery of the disk 8, and the wall of which is provided at diametrically opposite points with straight slots 21 (Figure 3), which extend parallel with the shaft 14 and in which engage the pins 19. Fixedly secured on the shaft 14 beyond the disk 18 is a similar disk 22 which is provided on its periphery with two pins 23 located, respectively, at diametrically opposite points on the periphery of the disk and which engage in diagonally disposed slots 24 provided in the wall of the head 20. This pin and slot engagement, as to one side of the head, is shown in Figure 1. The outer end of the shaft 14 is screwthreaded, as indicated at 25, (Figure 3), and mounted on this end to have screwthreaded engagement therewith is a hand wheel 26, which is rotatably mounted in the end wall of the head 20. From the construction described, it will be seen that if the hand wheel 16 is turned in a clockwise direction, the head 20 will be moved inward, the slots 21 passing over the pins 19. As this movement occurs, the walls of the inclined slots 24 engage the pins 23, which will cause the shaft 25 to turn, and this movement of the shaft will turn the disk 15 to cause the arms 16 to force the leaves 8 outward. If the hand wheel 26 be turned in an anti-clockwise direction, the parts will be moved in the opposite direction to that described to cause the leaves 8 to be moved inward. The head 20 is, of course, constantly rotated, and in order that the operator may regulate to a nicety the variation in the feed of the drum 5, we provide on said head a circular projection 27, which operates in the manner of a pointer and rotates in proximity to a graduated scale plate 28, secured above the head on the wall 4^a, as shown by Figure 3. It will be apparent that by turning the head to any one of the graduations on the scale plate, the operator can vary the feed to a greater or less extent in any amount desired, and these graduations can be suitably numbered, if desired, to show the quantitative feed which will be produced by turning the head to cause the projection 27 to rotate immediately under a given graduation.

Referring to Figures 3 and 4, the numerals 29 indicate, respectively, fixed curved partitions which extend between the heads 6 and 7 from the periphery of said heads to near the periphery of the disk 15, and are positioned so that the free ends of the leaves 8 will have sliding contact therewith in their movement. The inner end of each of the partitions 29 is provided with a stop 30, which limits the in-

ward movement of the corresponding leaf 8 associated therewith.

From an inspection of Figure 4, it will be seen that as the leaves 8 are moved inward, peripheral pockets 31 will be provided on the surface of the drum above each leaf, the bottom of which is formed by the leaf and the end wall of which is formed by the portion of the partition 29 extending above said leaf. The heads 6 and 7 rotate in close proximity to the front and rear walls of the casing 1, as shown by Figure 4, so that only the amount of the material, such as flour, for example, which can be contained by each pocket 31 in succession, can be carried past the point X of the front wall of the casing, said point indicating the point of closest approach of the heads 6 and 7 to the said front wall. It will thus be seen that for any given adjustment of the leaves 8 and with the drum 5 rotating at a uniform speed, substantially a uniform quantitative feed of material will result, and that the quantitative amount of this feed may be lessened or increased to a predetermined degree by simply lessening or increasing the size of the pockets 31 by turning the head 20, as previously described.

We wish it understood that the drawing illustrates a preferred embodiment of the invention, but that the broad idea thereof, as defined in the claims, is not limited to the special construction of apparatus shown.

We claim:

1. A feeding machine of the class described, comprising a casing affording an inlet and an outlet, a feed drum rotatably mounted in said casing between said inlet and outlet, a plurality of segmental members pivotally mounted at one end, a curved radially-disposed partition located in proximity to the free end of each of said segmental members, a shaft rotatably mounted in said casing, a disk on said shaft, and a series of arms each of which is pivotally connected at one end to the peripheral portion of said disk, and at the other, to the free end of a segmental member, means for rotating said feed drum, and means for manually turning said shaft in either direction adjustable distances, whereby to simultaneously move the free ends of all of said segmental members toward or from the periphery of said feed drum to vary the size of peripheral pockets formed on said feed drum by said segmental members and partitions.

2. A feeding machine of the class described, comprising a casing affording an inlet and an outlet for material, a feed drum rotatably mounted in the casing between said inlet and outlet and provided with a series of peripheral pockets having movable bottoms, a shaft rotatably mounted in said casing and operatively connected with all of said bottoms, whereby, upon turning said shaft in one direction or the other, said bottoms will be moved to vary the capacity of said pockets,

an indicating member mounted to rotate with said drum and longitudinally adjustable on said shaft and operatively connected therewith to turn the same, and a scale associated with said indicating member for indicating the extent of adjustment of the capacity of said pockets effected by manually operating said indicating member to turn said shaft.

3. A feeding machine of the class described, comprising a casing affording an inlet and an outlet for material, a feed drum having a series of peripheral pockets provided with movable bottoms, hollow trunnions rotatably supporting said feed drum in said casing, means for rotating said feed drum, a shaft rotatably mounted in said hollow trunnions, operatively connected with said bottoms to adjust the positions of the same when turned and having a screwthreaded end, and means for turning said shaft and for indicating the

extent of such adjustment comprising a disk fixedly secured on one of said trunnions and provided with two projections located, respectively, at opposite sides of its periphery, a hollow indicating member mounted on said disk and having longitudinal slots receiving said projections, a second disk mounted on said shaft and provided with two projections extending, respectively, from diametrically opposite sides of its periphery, said indicating member having inclined slots engaging said latter projections, a hand wheel rotatably mounted in said head and having screwthreaded engagement with said shaft, and a scale associated with said indicating member.

In testimony whereof, we have hereunto set our hands.

BURTON NEAL.

GEORGE H. HEBEBRAND.
